[57] CLAIM

The ornamental design for a glass oil lamp, as shown and described.

DESCRIPTION

FIG. 1 is a front elevation view of a glass oil lamp showing my new design; the undisclosed rear being the same in appearance except for the alignment of the lamp elements;

FIG. 2 is a top plan view thereof;

FIG. 3 is a left end elevation view thereof;

FIG. 4 is a right end elevation view thereof;
FIG. 5 is a front elevation view of a second embodiment of a glass oil lamp; the undisclosed rear being the same in appearance except for the alignment of the lamp elements;

FIG. 6 is a top plan view thereof;

FIG. 7 is a left end elevation view thereof; and,

FIG. 8 is a right end elevation view thereof.
